UNITED STATES PATENT OFFICE.

WILLIAM RUSHTON BOWKER AND JOHN RUSHTON BOWKER, OF WALTHAM, MASSACHUSETTS.

CAR-JOURNAL BEARING.

SPECIFICATION forming part of Letters Patent No. 591,808, dated October 19, 1897.

Application filed February 26, 1897. Serial No. 625,076. (No model.)

To all whom it may concern:

Be it known that we, WILLIAM RUSHTON BOWKER and JOHN RUSHTON BOWKER, residing at Waltham, in the county of Middlesex and State of Massachusetts, have invented a new and useful Improvement in Car-Journal and Locomotive Bearings, hereinafter called the "journal-box," of which the following is a specification.

Our invention relates to improvements in car-journal bearings; and the object of our improvements is to provide a continuous lubricated bearing for the journal. We attain this by the mechanism illustrated in the accompanying drawings.

Figure 1 is a front view of a journal and bearing with our improved lubricating devices shown in dotted lines. Fig. 2 is a longitudinal vertical section through Fig. 1, showing one of the lubricating devices, which will be hereinafter termed "wave-breakers." Fig. 3 is an end view opposite to Fig. 1. Fig. 4 is a horizontal section showing two of these wave-breakers located in diagonally opposite corners of the bottom of the journal-box, and Fig. 5 is a section on the diagonal line 5 5 of Fig. 4.

A is the journal-box, having the end bearings D D, and B is the journal. The bottom 30 of box A forms the oil-reservoir.

In the bottom of the box or oil-reservoir we place or form, preferably in diagonally opposite corners, the wave-breakers, which are so formed as to break the waves of oil caused by the vibrations of the car and splash or spray the same upwardly against the journal. These breakers C C fit the lower corners of the box or reservoir and have concaved faces, the upper ends of which terminate, as shown, 40 in sharp edges.

When the car is vibrated laterally in passing curves, crossings, &c., the oil will be forced into and upwardly by the concaved or inclined

faces of these breakers or deflectors C C till it reaches the upper overhanging edges, whereupon it will break into spray or splash upwardly upon the journal, the surplus oil falling back into the reservoir. It will be seen that this is a very simple and inexpensive means for lubricating journals and their bearings, and it is not to be confused with wings or flanges projecting over a reservoir to prevent the oil from escaping therefrom.

What we claim is—

1. The combination, with a car or locomotive journal-box the lower portion of which constitutes an oil-reservoir, of one or more wave-breakers in the said reservoir and shaped to break the oil-waves and splash or spray the oil upwardly against the journal, substantially as described.

2. The combination, with a car or locomotive journal-box the lower portion of which constitutes an oil-reservoir, of one or more wave-breakers located in the corners of the reservoir-bottom and having concavities or inclines to force the oil upwardly toward the journal and overhanging edges at the upper ends of the concavities to break the waves and cause the oil to splash or spray upwardly onto the journal, substantially as described.

3. The combination, with a car or locomotive journal-box, the lower portion of which constitutes an oil-reservoir, of breakers located in diagonally opposite lower corners of the reservoir and having their opposed faces concaved and terminating in overhanging edges to break the ascending waves of oil and splash or spray the same upwardly against the journal, substantially as described.

WILLIAM RUSHTON BOWKER.
